UNITED STATES PATENT OFFICE.

JAMES W. SCOTT, OF UHRICHSVILLE, OHIO.

POTATO-DIGGER.

SPECIFICATION forming part of Letters Patent No. 364,443, dated June 7, 1887.

Application filed November 15, 1886. Serial No. 218,912. (No model.)

To all whom it may concern:

Be it known that I, JAMES W. SCOTT, of Uhrichsville, in the county of Tuscarawas and State of Ohio, have invented a new and Improved Potato-Digger, of which the following is a full, clear, and exact description.

The object of my invention is to provide a new and improved potato-digger which is simple and durable in construction and very effective in operation.

The invention consists of various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a plan view of my improvement. Fig. 2 is a side elevation of the same. Fig. 3 is a sectional side elevation of the same on the line *x x* of Fig. 1, and Fig. 4 is a vertical cross-section of the same on the line *y y* of Fig. 3.

The frame A, of suitable construction, is mounted on the axle B, carrying the driving-wheels C and C', each provided with the internal gear-wheel, D, into which meshes the pinion D', attached to the shaft E, mounted in suitable bearings on the plow-frame, fulcrumed on the main axle, and provided on its front cross-beam, F', with a standard, G, on which is mounted a shaft, H, carrying a pinion, H', which meshes into rack-teeth formed on the frame I, secured to the tongue A'.

On the shaft H is fastened a crank-arm, J, carrying a swinging hand-lever, J', which operates a pawl, J'', engaging a ratchet-wheel, J'', cast on the standard G.

The plow-frame F carries on its rear ends two beams, to which is secured by bolts the plow or scraper F'', of suitable construction. On the rear end of the plow or scraper F'' is situated the shaker K, which is provided with a number of slats or bars, K', pivoted at their inner ends to the bottom plate of the said scraper F'', and united with each other by the cross-bar K'', pivotally connected with each of the said slats K'. One end of the cross-bar K'' is provided with the screw L, pivotally connected with the forked arm L, fulcrumed on one side of the plow-frame F. On the other end of the bar K'' is a similar screw, L'',

which is pivotally connected with the double-forked arm N, fulcrumed by its upper fork on the lever O, pivoted on an arm, F', extending from the rear of the plow-frame F.

The upper end of the lever O connects, by the link P, with the screw-rod Q, screwing in the horizontal lever-frame R, pivoted on top of the plow-frame F, and connected by the eccentric-rod S with the eccentric T, placed loosely on the pinion-shaft E, and provided on its hub with clutch-teeth, which engage the clutch U, mounted to slide on and rotate with the said shaft E.

A forked lever, V, pivoted on the plow-frame F, serves to throw the clutch U in and out of gear with the eccentric T. The outer end of the lever V will be held in a locked position on the lug W, attached to the frame F. The machine is provided with the usual driver's seat and tongue.

The operation is as follows: The plow or scraper F'' can be raised out of the ground or let into the ground to any desired depth by moving the crank-arm J forward or backward, after first withdrawing the pawl J'' from the ratchet-wheel J'', so that the pinion H', acting on the rack-teeth of the stationary frame I, causes a swinging motion of the plow-frame F, fulcrumed on the axle B, so that the scraper F'' is raised or lowered. When the machine is moved forward, the gear-wheel D on the driving-wheel C imparts a rotary motion to the shaft E and its clutch U by means of the pinion D'. When the clutch is thrown in gear with the eccentric T, by means of the lever V, then a swinging motion is imparted to the frame R, which, by means of the screw Q and the link P, imparts a sidewise rocking motion to the lever O, fulcrumed on the arm F', and this motion is transmitted by the arm N to the shaker K, so that the latter swings sidewise and up and down, on account of having its cross-bar K'' pivotally connected to the arms L' and N on the sides of the machine. It will be seen that by this rocking motion of the shaker the slats K' will swing sidewise independently, on account of being fulcrumed with their inner ends on the bottom plate of the scraper F''. Thus the ground and the potatoes, which pass over the bottom plate of the scraper toward the rear and upon the shaker K, are thoroughly agitated and separated by the rock-

ing motion of the shaker K, so that the latter swings sidewise and up and down, on account of having its cross-bar K'' pivotally connected to the arms L' and N on the sides of the machine. It will be seen that by this rocking motion of the shaker the slats K' will swing sidewise independently, on account of being fulcrumed with their inner ends on the bottom plate of the scraper F''. Thus the ground and the potatoes, which pass over the bottom plate of the scraper toward the rear and upon the shaker K, are thoroughly agitated and separated by the rock-

ing motion of said shaker K. The cross-bar K² can be raised and lowered by adjusting the screw ends L and L² of the forked lower ends of the arms L' and N, as shown in Fig. 4. The 5 relative motion of the shaker is increased or diminished by lengthening or shortening the screw-rod Q, thus giving more or less swing to the shaker, as desired.

Having thus described my invention, what 10 I claim as new, and desire to secure by Letters Patent, is—

1. The combination, with the wheels, the axle, the frame connected between its ends to the axle and the tongue extended rearward 15 over the front part of the frame and secured to the axle, of the standard G, projecting upward from the front end of the frame alongside of the tongue, and provided with the transverse shaft, an operating lever, and a pinion, 20 H', and the open frame I, connected at its lower end to the tongue and receiving the said pinion, and having teeth on one vertical inner edge engaging said pinion, substantially as set forth.
- 25 2. The combination, with the frame, the axle, and the drive-wheels, of the scraper, the shaker having rearwardly-extending slats pivotally connected at their inner ends to the scraper to swing horizontally, and means for 30 reciprocating said slats simultaneously, substantially as set forth.
3. The combination, with the scraper of a potato-digger, of a series of horizontally swinging slats pivotally connected at their inner 35 ends to the rear edge of the scraper and a cross-bar pivotally connected to each slat, suspension-rods pivotally connected to said cross-bar at their lower ends, and one of said rods pivoted to the frame, or a part thereof, at its 40 upper end, an upwardly-extending lever pivoted near its lower end on the rear end of the frame, or a part thereof, and connected to the upper end of the other suspension-rod, and means for 45 rocking said lever laterally, substantially as set forth.
4. In a potato-digger, the driving-wheels C and C', the axle B, on which the wheels are

mounted, the gear-wheels D, attached to the said driving-wheels, the pinions D', meshing into the said gear-wheel, the shaft E, carrying 50 the said pinion, and the plow-frame F, on which the said shaft is mounted, said frame being fulcrumed on the axle B and provided with the scraper F², in combination with the shaker K, consisting of the slats K', pivoted at their inner ends on the bottom plate of the said scraper F², the cross-bar K², uniting the said slats K', and means for imparting a sidewise motion to the said cross-bar from the said shaft E, substantially as shown and described. 55

5. In a potato-digger, the plow-frame F, carrying the scraper F² and the shaft E, the shaker K, provided with slats K', pivoted to the bottom plate of the scraper F², and the cross-bar K², pivotally connected to the said slats K', in 60 combination with the pivoted arms L' and N, connected with the said cross-bar K², the lever O, connected with the said arm N, the pivoted frame R, connected with the said lever O by means of screw Q and the link P, the eccentric-rod S, operating on the said frame R, and the eccentric T, placed on the said shaft E and rotating with the same when engaged with the clutch U, substantially as shown and described. 70

6. In a potato-digger, the scraper F², in 75 combination with the slats K', pivoted on the said scraper, the cross-bar K², connecting the said slats K', the screws L and L² on the said cross-bar K², the arms L' and N, pivotally connected with the said screws, and means for 80 imparting a rocking motion to the said arm N, substantially as shown and described.

7. The combination, with the frame, the axle, the drive-wheels, and the scraper, of the shaker at the rear of the scraper and the horizontally- 85 swinging frame pivoted on the main frame, and having a longitudinally-adjustable screw in connection with the shaker and operated from the drive-wheels, substantially as set forth.
